UNITED STATES PATENT OFFICE.

HARRY ALBERT GRIFFITHS, OF BIRMINGHAM, AND RICHARD HANSON GRIFFITHS,
OF SUTTON COLDFIELD, ENGLAND.

SHEET-METAL-BLANK FEEDER.

1,394,006.

Specification of Letters Patent. Patented Oct. 18, 1921.

Application filed February 14, 1921. Serial No. 444,835.

To all whom it may concern:

Be it known that we, HARRY ALBERT GRIFFITHS, residing at 8 Chad road, Edgbaston, in the city of Birmingham, England, and 5 RICHARD HANSON GRIFFITHS, residing at Highfield, Sutton Coldfield, in the county of Warwick, England, subjects of the King of Great Britain and Ireland, have invented certain new and useful Sheet-Metal-Blank 10 Feeders, of which the following is a specification.

This invention relates to mechanically actuated presses for operating on circular or other sheet metal blanks, and has for its 15 object to provide improved automatic feeding mechanisms of the type in which the bottom blank of a stack of superimposed blanks is separated from those above it by means of a knife or a plurality of knives 20 and subsequently fed to the press tools by gravity or otherwise.

The invention comprises the employment in conjunction with an oscillatory knife, of an oscillatory support for the stack of 25 blanks, the support being adapted to release the bottom blank after the knife has engaged the stack.

The invention also comprises the use of a pair of oscillatory knives adapted to operate in succession and herein termed primary and secondary knives, and the arrangement in conjunction with the secondary knife of an oscillatory support adapted to serve as the sole or principal 30 support for the stack of blanks, this support being caused to release the bottom blank after the secondary knife has passed into position for supporting the superincumbent blanks.

40 In the accompanying sheets of explanatory drawings:

Figure 1 is a plan and Fig. 2 a front elevation of one form of blank feeding mechanism constructed in accordance with this 45 invention.

The primary knife *a* is secured at the upper end of an oscillatory spindle *b*. This knife is in the form of a relatively small disk having a knife edge and having a portion of its periphery cut away so that the adjacent portion of the stack of circular sheet metal blanks *c* can rest on a support *d* which is also secured to the spindle. The support is in the form of a circular disk 50 which has a portion of its periphery cut

away so that it can leave the blanks. The distance between the upper face of the support and the lower face of the knife is equal to the thickness of a blank. Referring to Fig. 1, the support is there shown in engagement with the underside of the stack of blanks. On rotating the knife and support in the direction of the arrow, the knife first enters the stack immediately above the lower blank and lifts the other blanks. 60

After the knife has entered sufficiently far the support leaves the bottom blank, but the latter is not yet free to fall away because it is still carried by another support to be hereinafter described. Motion is imparted 70 to the primary knife *a* and support *d* by a lever *e* secured to the lower end of the spindle *b* and actuated in one direction by a link *f* which receives motion from another link *g* connected to any convenient moving part of 75 the press mechanism. Motion in the return direction may be effected by a spring *h*.

Adjacent to the primary knife is arranged the secondary knife *i*. This consists of a broad oscillatory blade pivoted at *j* and 80 actuated by a link *k* connected to the above mentioned link *g*; both knives move together. The return motion may be given to the knife *i* by a spring *l*. The disposition of the knife *i* in relation to the knife *a* is such 85 (as shown in Fig. 1), that the knife *a* first enters the stack of blanks and produces an opening into which the secondary knife *i* can enter. The knife *i* then separates the stack completely from the bottom blank. 90

Secured to the knife *i* is the support *m*. This also consists of a broad blade which normally acts as the main support for the stack of blanks. While the knife *i* is entering the stack, the support *m* is moving away, 95 and finally when the knife *i* is fully in position, the support *m* is clear of the bottom blank. Meanwhile the support *d* has also moved clear of the bottom blank, and the latter is therefore free to fall away on to an inclined or other table whence it can pass by gravity or otherwise to the press tools. In the return of the knives, the support *m* comes into its active position before the knife *i* leaves the blanks. As soon as the 105 knife *i* is clear of the blanks, the stack falls on to the support *m* which now carries the stack prior to a repetition of the operations above described. It will be understood that the vertical distance between the knife *i* and 110

support *m* is equal to or rather greater than the thickness of the blank.

Lateral displacement of the blanks forming the stack is prevented by three upright guides *n* between which the stack of blanks is free to move. Usually it is found advantageous to load the stack by a weight *o* as shown in Fig. 2. The weight serves to hold the stack firmly on the supports when the mechanism is operating at high speed.

* The invention is capable of being carried out in a variety of ways. Thus, the oscillatory motions of the knives and supports may be reciprocatory or linear instead of angular or rotary as above described. If desired the knife *a* and support *d* may move with an angular motion as described and the knife *i* and support *m* with a rectilinear motion. Also one or both of the supports, instead of being rigidly connected to its knife may have a certain degree of freedom permitting the knife to move through a convenient distance independently of the support. In the mechanism illustrated the support *d* may be dispensed with. As a further alternative the knife *i* and support *m* may be dispensed with in which case two or more knives as *a* and supports as *d* are arranged at suitable positions relatively to the stack of blanks and caused to act on the stack simultaneously.

The invention is not limited to any particular mechanical details as these may be varied to meet different requirements.

Having thus described our invention what we claim as new and desire to secure by Letters Patent is:—

1. In mechanism for individually feeding sheet metal blanks from a stack to the tools of a press, the combination of a pair of oscillatory separating tools, a support arranged

in conjunction with one of the tools, and means for actuating the separating tools and support so that one of the separating tools first enters the stack of the blanks and forms an aperture between the bottom blank and those above it, and then the second separating tool enters and completely separates the bottom blank from the stack, the support meanwhile moving and finally allowing the bottom blank to fall away when the second separating tool has sufficiently entered the stack to support the blanks above it, substantially as described.

2. In mechanisms for individually feeding sheet metal blanks from a stack to the tools of a press, the combination of an oscillatory support for a stack of blanks, a separating tool arranged in conjunction with the support, the underside of the tool being in a plane which is separated from that containing the upper surface of the support by a distance equal or approximately equal to the thickness of the blanks, and the mutual arrangement of the separating tool and support being such that the one moves into its operative position before the other is withdrawn from the stack, an additional oscillatory separating tool adapted to produce an aperture in one side of the stack of blanks prior to the entry of the first mentioned separating tool, springs for actuating the parts in one direction, and link and lever mechanisms for actuating the parts in the opposite direction, and guides for laterally supporting the stack of blanks, substantially as described.

In testimony whereof we have signed our names to this specification.

HARRY ALBERT GRIFFITHS.

RICHARD HANSON GRIFFITHS.
